UNITED STATES PATENT OFFICE.

FREDERICK R. ROBERTS, OF CONCORD, NEW HAMPSHIRE, ASSIGNOR TO
GEORGE F. DURGIN, ALLAN H. ROBINSON, AND GEORGE H. MOSES, OF
SAME PLACE.

DESIGN FOR A HANDLE FOR SPOONS OR SIMILAR ARTICLES.

SPECIFICATION forming part of Design No. 30,043, dated January 24, 1899.

Application filed November 9, 1898. Serial No. 695,988. Term of patent 14 years.

To all whom it may concern:

Be it known that I, FREDERICK R. ROBERTS, a citizen of the United States, residing at Concord, in the county of Merrimac and State of New Hampshire, have invented and produced a new and original Design for a Handle for Spoons or Similar Articles; and I do hereby declare the following to be a full, clear, and exact description of the same, reference being had to the accompanying drawings, forming a part thereof.

This invention relates to an original design for a handle for spoons and similar articles, and it is embodied in the design hereinafter described, and shown in the accompanying drawings.

In the drawings, in Figure 1 is shown a front or obverse view of a spoon embodying the design, and in Fig. 2 is shown the reverse or back thereof.

As represented in the drawings, the handle portion is in general outlines of the conventional shape—that is, it has the narrow central and base parts and the enlarged or broadened outer end. On the front or obverse face the edges of the handle are decorated by the fanciful scrollwork and beading A. At the extreme end of the handle is a representation of a sunburst or corona B, 30 having at its center or on its face a representation of a cross and crown. Immediately below these representations is a portrait representing Mrs. Mary Baker Eddy, founder of the school of Christian Science, the same oc-

cupying a portion of the field inclosed by the border at the broad end of the handle. Below the portrait is a floral representation C, and on the field immediately below may be placed suitable words. Floral representations D E are placed adjacent the center and 40 at the base of the handle. On the reverse the edges of the handle are decorated by fanciful scrollwork and beading, and at the end thereof is represented a corona having represented centrally thereof a cross and crown, 45 all of which are similar in general appearance to the corresponding decorations on the obverse. Below the corona is a field on which may appear any suitable printed matter. Below this field is a floral representation C', below which is a plain field. A floral representation D' appears below this latter plain field.

The bowl F has on its obverse or concaved surface the representation of a dwelling-house.

Having thus described the invention, what is claimed as new, and desired to be secured by Design Letters Patent, is—

The design for a handle for a spoon or similar article substantially as shown and described.

In testimony whereof I affix my signature in presence of two witnesses.

FREDERICK R. ROBERTS.
